UNITED STATES PATENT OFFICE.

EDWIN DENSMORE, OF CORONADO, CALIFORNIA.

MANUFACTURE OF WOODEN BOXES.

SPECIFICATION forming part of Letters Patent No. 403,333, dated May 14, 1889.

Application filed December 1, 1888. Serial No. 292,425. (No model.)

To all whom it may concern:

Be it known that I, EDWIN DENSMORE, of Coronado, in the county of San Diego and State of California, have invented a new and useful Improvement in the Manufacture of Wooden Boxes; and I do hereby declare that the following is a full, clear, and exact description of the same.

In the manufacture of wooden boxes for the shipment of fruit it is customary to make one form of box out of two pieces of thin material, of a suitable width, laid across each other at right angles and with the ends turned up to form the depth of the box, the upper edges being connected by a binding-strip of tin, which is doubled or bent in U shape to embrace the inner and outer faces of the upper edges of the box, and thus hold them together in box form without the addition of other fastening devices. Heretofore such fastening devices have been placed upon boxes by hand; and it is the object of my invention to provide a simple form of apparatus by means of which these strips may be applied without hand-labor and more quickly than at present.

The invention consists of a suitable former for receiving the body of the box and a series of clinching-faces pivoted so as to move away from and toward the face of the former, whereby the strip is securely bound to the edges of the box and prevented from displacement.

The invention further consists of a former for the box, pivoted clinching-levers, and toggles connecting the ends of the clinching-levers for giving simultaneous movement thereto, and means for operating the toggles.

Finally, the invention consists in details of construction.

In the drawings, Figure 1 represents a side elevation, partly in section, of the former and two of the clinching-levers, one position of the levers being shown in dotted lines and the other in full lines, the operating-shaft and means for giving movement thereto being also shown. Fig. 2 is a face view of the former and clinching-levers. Fig. 3 is a detail view of one of the clinching-levers. Fig. 4 represents a side elevation of the machine, with its frame-work.

At A in Fig. 4 I represent the frame-work

of my machine, which is composed of uprights and cross-pieces suitably connected together by bolts, with the upper front corner formed on an angle, so as to bring the working parts 55 in position for the operator. A metal supporting-plate is secured to the inclined portion of the supporting-frame, as shown at B, and secured to this base-plate is a former, C, which is approximately the shape of the box 60 to be made, and is shown in Figs. 1 and 4 projecting outwardly beyond the face of the base-plate. The edges of the former are inclined as shown. The base-plate is cut away on all sides of the former, immediately bordering on 65 the edges thereof, and in the recesses thus formed the ends of the pointed levers project, the said levers being pivoted in the base-plate on the projecting ends of a pin which passes entirely through the front end from side to 70 side, as shown in Figs. 1 and 2. These levers are four in number, one being pivoted in each recess in the base-plate, and each lever consists of a shank, a, and a front portion formed of a series of projections with spaces between 75 and having a face-plate, b, extending across the front ends of the projections and secured thereto by means of screws, as shown. This face-plate has a concave edge which overhangs the upper edge of the former C. As 80 stated, the forward ends of the levers are pivoted, as shown at c, and the rear ends extend, forming long arms, which are bifurcated, and these arms are connected by means of short links d to a collar, e, which is rigidly secured 85 to the reciprocating shaft L. As these short links d are connected at one end to the arms of the levers a and at the other end to the moving collar e, each pair of links constitute, with the collar, toggle-levers, and positively 90 operate upon the arms of the levers a in the forward and backward movement of the shaft L.

The front end of the shaft has its bearings in a central opening in the former C, and on its rear end carries a coiled spring, G, the outer end of which bears against a stop, H, and the front end of which may be adjusted in tension by means of a stop, F, on the shaft controlled by a set-screw. The binding-strip, 100 which has been previously folded in U shape and bent to conform to the size of the upper

part of the box to be bound, is placed upon the former with the open part of the **U** in the front. The two pieces composing the body of the box are placed across the front of the former, one on top of the other, with their long ends at right angles, and these ends are folded around the edge of the former. The edges of the pieces are then inserted within the folds of the binding-strip. At this time the shaft 10 is in its forward position and the rear ends of the levers in their lowest position, and their front ends are raised. When the strips are in proper position, the shaft **L** is moved to the rear, which straightens the toggles and 15 lifts the rear ends of the levers, thus forcing the front ends down, causing the edge of the face-plate to clutch the edge of the folded tin strip and press it firmly to the edges of the wood, and the box is thus bound.

20 In order to give movement to the shaft, I provide a segment, **I**, which is provided in line with the stop **F** on the shaft. The spring **G** tends constantly to throw the shaft forward to raise the front ends of the clinching-levers, 25 and when it is desired to force the front ends downward the cam-segment is operated by means of a friction-roller, **J**, or any other means, and the arm of the segment bearing against the stop **F** forces the shaft to the rear 30 against the pressure of the spring, so as to operate to press the metal strip in place. The movement of the segment may be so timed that as soon as the operation of pinching is completed the segment may be disconnected from its driving-roller, and the spring **G** will 35 thus exert its force, and by throwing forward the lever release the box from the clinching-levers.

40 The binding is preferably formed in two sections and united by solder. In binding the

strip in square shape the corners are preferably rounded and the folds at this point pressed together.

I claim as my invention—

1. A machine for securing binding-strips to 45 boxes, consisting of a former for the boxes, a pivoted lever on each side of the former, each of said levers having its front end projecting over or beyond the rear edge of the base of the former, whereby said levers are adapted 50 to press the binding-strips securely over the front edges of the box, and means for operating said levers, substantially as described.

2. In combination with a former, pivoted levers **a**, arranged with their forward faces in 55 line with the base of the former, a reciprocating shaft, **L**, a collar carried on said shaft, and links **d** between the collar and pivoted levers, substantially as described.

3. In combination, a former, pivoted levers 60 with means for operating them, and a face-plate having a concave edge extending across the end of each lever, substantially as described.

4. In combination, a former, pivoted levers 65 having their front edges in line with the base of said former, one of said levers arranged at each side, a reciprocating shaft, toggle-levers between said shaft and pivoted levers, means for moving said shaft in one direction, and a 70 spring for operating the shaft in the other direction, substantially as described.

In testimony whereof I have signed my name to this specification in the presence of two subscribing witnesses.

EDWIN DENSMORE.
